GEORGE W. NOE,

By *H. Woodward*, Attorney

UNITED STATES PATENT OFFICE.

GEORGE W. NOE, OF CLINTON, MISSOURI.

SPARK-PLUG.

1,356,782.

Specification of Letters Patent. Patented Oct. 26, 1920.

Application filed October 20, 1919. Serial No. 331,814.

To all whom it may concern:

Be it known that I, GEORGE W. NOE, a citizen of the United States, residing at Clinton, in the county of Henry and State 5 of Missouri, have invented certain new and useful Improvements in Spark-Plugs, of which the following is a specification.

The invention has for an object to effect improvements in spark plugs whereby the 10 efficiency of such devices will be increased, especially by reducing the liability to fouling by carbon accumulations. A further aim is to effect an improvement in the specific construction whereby accumulation of 15 carbon on the porcelain is prevented; and another aim is to give a cage construction of an improved form upon the shell or casing. A still further aim is to effect improvements 20 in spark plugs whereby the efficiency of such devices will be increased, especially by reducing the liability of fouling by oil accumulations.

Additional objects, advantages and features of invention will appear from the construction, arrangement and combination of parts hereinafter described and shown in 25 the drawings, wherein,

Figure 1 is an elevational view of a plug constructed in accordance with my invention. 30

Fig. 2 is a vertical sectional view thereof. Fig. 3 is a detail of one of the openings in the cage portion of the shell,

Fig. 4 is a detail of the shell.

Fig. 5 is a longitudinal sectional view of a 35 further preferred embodiment of the invention.

There is illustrated a plug comprising a casing 10 threaded at 11 in the usual manner 40 for engagement in the tapped plug opening of an internal combustion motor cylinder, the upper part being hexagonal to permit its manipulation by a wrench, and suitably enlarged to receive a shouldered porcelain 45 as will be described. The interior of the lower portion is cylindrical in form terminating at the inner end in a shoulder 12, and upon the end portion of the plug there is formed a cage 13, comprising a semi- 50 spherical wall having a plurality of apertures 14 therein and one large central aperture 15. The apertures 14 consist of outer recessed portions 16 of large diameter with a reduced inner bore 17, terminating in a 55 small cone 18 at the outer end, extending outwardly into the recess 16 a distance, but

stopping short of the projected periphery of the cage 13. Engaged in the casing there is a porcelain 19 having an inner end portion snugly fitted in the cylindrical inner 60 part of the casing 10 abutting against a gasket 20 set upon the shoulder 12, the porcelain having a large shoulder 21 against which there may engage a gland 22 screwed into the outer part of the casing, which is 65 suitably threaded upon the interior for the purpose. An electrode 23 is cast or otherwise suitably secured positively in the porcelain, and the inner end of the porcelain is planiform and extends snugly against the 70 electrode, which is projected beyond this planiform surface of the porcelain very slightly, in practice in the neighborhood of or less than one-sixty-fourth of an inch. Terminal connections 25 are provided at 75 the outer end of the electrode. The cage 13 is formed so as to be concentric with the inner end of the electrode, and disposed loosely within the cage there is a ball 26 which serves as a ground electrode, being 80 of a size to form a gap between itself and the electrode 23 suitable for the jump spark ordinarily used in systems employing such plugs.

It will be seen that throughout any movement of the ball 26, it can never be at a greater distance from the electrode than will give a proper gap for the spark to jump in ordinary systems, but by the action of gases injected through the apertures 14 it may at 90 95 times be blown into contact with the electrode or with the surfaces of the porcelain thereadjacent, and by its movement keep the porcelain surface clear of carbon for a distance sufficient to prevent a short circuit. The bores 17 are on an axis intersecting the lower face of the porcelain near its outer 100 part, so that jets of incandescent gas are projected against the porcelain, tending to knock or brush off any carbon which may accumulate. The gas entering through the bores 17 also serves to agitate the balls in the cage causing removal of carbon by abrasion.

In Fig. 5, there is shown a larger porcelain 19', the construction of the porcelain and its manner of mounting being otherwise the same as before described. The electrode, however, terminates flush with the end face of the porcelain. Within the cage 13', however, there are inclosed a plurality 110 of balls, one large one 27 forming the medium through which the high tension

current passes to or from the electrode 23', while in addition there are a number of smaller balls 28 whose function is solely to aid in cleaning the interior of the cage and 5 porcelain 19', these balls being adapted to engage surfaces of the porcelain farther from the electrode than can be reached by the larger ball. These smaller balls are preferably of such size and number that liability of the larger ball to be raised thereon so as to short circuit the plug is obviated. It may be found desirable to reduce or increase the number beyond that shown in the 10 drawing.

15 What is claimed:

A plug of the character described comprising a casing having a terminal cage comprising a semi-spherical wall having a plurality of recesses in its outer side and

respective central apertures through the 20 wall, said apertures having cone-shaped terminal portions therearound within said recesses stopping short of a projection of the outer surface of the cage, a porcelain mounted in the plug and having its inner face exposed within the cage, an electrode in the porcelain slightly projected therefrom concentrically of the cage, and a ball member loosely disposed within the cage of a size to form a spark gap between the electrode and 25 the ball.

In testimony whereof I have affixed my signature in presence of two witnesses.

GEORGE W. NOE.

Witnesses:

DENNIS SIMMS,
E. F. ALLEN.
